UNITED STATES PATENT OFFICE.

ABIRAM J. SLONECKER, OF TRENTON, MISSOURI.

MEANS FOR CONVERTING MOTION.

1,188,016.

Specification of Letters Patent. Patented June 20, 1916.

Application filed October 20, 1914. Serial No. 867,638.

To all whom it may concern:

Be it known that I, ABIRAM J. SLONECKER, a citizen of the United States, residing at Trenton, in the county of Grundy and State of Missouri, have invented a new and useful Means for Converting Motion, of which the following is a specification.

The present invention relates to improvements in internal combustion engines, one object of the invention being the provision of an engine of this character, in which the reciprocating movement of the piston is transmitted in a rotary movement to the crank shaft through a peculiarly arranged and mounted gyratory member, so that the greatest possible speed and power may be obtained from a minimum amount of fuel, the engine being made exceedingly light so as to be used in connection with aeroplanes, dirigibles, for marine purposes, and for any use where the present construction of reciprocating explosion engine is employed.

A further object of the present invention, is the provision of an explosion engine of this type, in which the piston rods are so connected as to have imparted thereto during the reciprocation thereof, a slight spiral movement to assist in the easy movement thereof, for it has been discovered that if the piston is slightly oscillated during the reciprocation, that is upon its axis, that it will more easily slide within the cylinder.

A still further object of the invention, is the provision of an engine of this character, in which the gyratory member and the connecting parts thereof are lubricated from a main source, this gyratory member itself being made hollow and thus constituting the oil receptacle.

A still further object of the present invention, is the provision of a simple, inexpensive and durable engine of this character, which is exceedingly light in construction, and which for given weight will develop greater horse power and speed with a minimum amount of fuel, thus producing a thoroughly efficient and practical engine.

With the foregoing and other objects in view which will appear as the description proceeds, the invention resides in the combination and arrangement of parts and in the details of construction hereinafter de-

scribed and claimed, it being understood that changes in the precise embodiment of the invention herein disclosed can be made within the scope of what is claimed without departing from the spirit of the invention.

In the drawings, Figure 1 is a longitudinal section taken through the complete engine, the crank shaft, fly wheel and two of the pistons being shown in elevation. Fig. 2 is a section taken on line 2-2 of Fig. 1. Fig. 3 is a view in elevation of the gyratory member, a portion of the crank shaft being shown in section. Fig. 4 is an enlarged detail view showing the method of connecting the gyratory member to one of the piston rods. Fig. 5 is a view similar to Fig. 1 of a modified form of the present invention. Fig. 6 is a cross section through the gyratory member showing a modified method of attaching the same to a straight shaft.

Referring to the drawings, the numerals 1 and 2 designate the opposite heads or members of the engine, the same being provided respectively with the shaft bearings 3 and 4 for the reception of the axially disposed shaft 5, the same being provided with the crank 6 intermediate of its ends and such crank being disposed at an angle of approximately $22\frac{1}{2}$ degrees. The crank portion has disposed thereupon so as to rotate therewith in as the same is gyrated, the hollow gyratory member 7, having the two bearing sleeves 8, which are separated centrally of the member so that the lubricant within the member 7, may be readily directed upon the shaft and thus lubricate the sleeves during the rotation of the shaft. The thrust bearings 9 are disposed upon the crank 6 at opposite sides of the gyratory member 7 so as to take care of the thrust imparted to the gyratory member in the transmission from the reciprocation of the pistons 17 and 18 to the rotation of the shaft 5.

Formed integral with or carried at the periphery of the gyratory member 7 are a plurality of radial stems 10, each one of which is provided with a ball 11 which in turn fits within the socket 12 formed by the two coupling members 14, which have the coupling flanges 13, said coupling members or sleeves 14 being keyed at 15 at the junction of the piston rods or shafts 16 and 16', as

particularly illustrated in Figs. 1 and 4. Each rod 16-16' is provided with its piston 17 or 18, so that such pistons oppose each other and are co-axial relative to each other.

5 The respective members 1 and 2 carry a plurality of cylinders 19 and 20 in which the respective pairs of pistons 17 and 18 are mounted for reciprocation, the intake and exhaust valves to the respective cylinders 10 and the means for operating the same, not being shown.

In order to provide a means for lubricating the ball and socket joint between the balls 11 and the sockets 12, the periphery 15 of the member 7 is provided with the radial lubricant ports 21, through which the lubricant may be directed, as clearly illustrated in Figs. 2 and 4 so as to lubricate the outer surface of the ball and the inner surface of 20 the socket. Where the ball and socket joint is upon the upper side of the member 7, as illustrated in Fig. 2, the wicks 22 are connected to the ports 21, and the lower ends of such wicks are disposed within the lubricant 25 within the member 7 so that the lubricant will be supplied thereto by capillary attraction. Thus the member 7 contains lubricant for lubricating bearings at 6 and 8 and for lubricating the ball and socket joints between 30 the coupling members 14 and the gyroscopic member 7.

In the construction of engine shown in Fig. 5, the member 2' is the only one employed, the shaft 5' being journaled therein 35 and having the crank 6', the opposite end of the shaft 5' being journaled in the standard 23 and having the thrust bearing 24 at the inner face thereof, while the thrust bearing 25 is at the outer face of the member 2', thus 40 taking care of the thrust from the respective pistons 18' mounted in the cylinders 20' and which are connected to the gyroscopic member 7' through the piston rods 16', the coupling 14' being constructed somewhat similar to 45 the one heretofore described except that the outer coupling 14' is a sealing coupling and fits over the end of the respective shaft or piston rods 16'.

It will be seen that in both of these constructions that due to the gyroscopic movement imparted to the member 7', that the piston rods 16-16' and 16' have a slight oscillatory movement imparted thereto so as to impart a slight spiral movement to the 55 respective pistons 17, 18 and 18' during the reciprocation of the same within their cylinders. This movement assists in the lubricating and sliding action of the same and makes such action more easy.

60 In the construction shown in Fig. 6, the shaft 5 is a straight shaft, a sleeve 26 which is provided with a bore 27 whose ends are eccentric to the body thereof and which are longitudinal thereof, is fixed upon the 65 straight shaft 5 and held against rotation

by means of the keys 28. Thus the gyroscopic member 7' with its bearing portion 8' is mounted for rotation upon the sleeve 26 which being disposed at the angle of approximately 22 $\frac{1}{2}$ degrees to the shaft 5', will 70 during the gyroscopic movement imparted to the member 7' impart the desired rotation to the shaft 5'.

From the foregoing description, taken in connection with the drawings, it is evident 75 that with an engine constructed according to and embodying the present invention, that an exceedingly light, durable and powerful engine is produced, inasmuch as any number of double acting or single acting cylinders 80 may be employed and connected peripherally to the gyroscopic members 7, 7' or 7'' so that such gyroscopic movement will be converted into a rotary movement in the shafts 5, 5' or 5'' to thus impart the maximum 85 power and speed thereto with the minimum use of fuel in the operation of the various pistons. In the present instance a jump spark system employing the spark plugs 29 is used, but it is apparent that any system 90 that will produce the desired ignition of the charge may be employed.

What is claimed is:

1. The combination with a supporting structure, of an approximately horizontal shaft journaled therein; a hollow oil container mounted on the shaft and disposed in a plane at an acute angle to the axis of the shaft; a member mounted for right line reciprocation parallel to the axis of the shaft and disposed below the shaft; and a driving connection between the said member and the container, the container having a port discharging upon the connection to effect a lubrication thereof. 100

2. The combination with a supporting structure, of an approximately horizontal shaft journaled therein; a hollow oil container mounted on the shaft and disposed in a plane at an acute angle to the axis of the shaft; a member mounted for right line reciprocation parallel to the axis of the shaft and disposed above the shaft; a driving connection between said member and the container; and a wick leading from the interior 110 of the container to the connection to effect a lubrication thereof. 115

3. The combination with a supporting structure, of an approximately horizontal shaft journaled therein; a hollow oil container mounted on the shaft and disposed in a plane at an acute angle to the axis of the shaft; a member mounted for right line reciprocation parallel to the axis of the shaft and disposed below the shaft; a member mounted for right line reciprocation parallel to the axis of the shaft and disposed above the shaft; driving connections uniting said members operatively with the container, the container having a port discharging upon 120 125 130

the connection of the lower reciprocating member and constituting a means for lubricating said connection; and a wick leading from the container to the connection of the 5 upper reciprocating member, to effect a lubrication thereof.

In testimony that I claim the foregoing

as my own, I have hereto affixed my signature in the presence of two witnesses.

ABIRAM J. SLONECKER.
